(57) **CLAIM**

The ornamental design of a truck bed side rail cleat, as
shown and described.

DESCRIPTION

FIG. 1 is a perspective view of a truck bed side rail cleat;
FIG. 2 is a right side elevational view of a truck bed side rail
cleat;

FIG. 3 is a bottom plan view of a truck bed side rail cleat;
FIG. 4 is a front elevational view of a truck bed side rail
cleat; and,

FIG. 5 is a top plan view of a truck bed side rail cleat.
The broken line portions of the drawings are shown for
illustrative purposes and form no part of the present invention.
